UNITED STATES PATENT OFFICE.

WILLIAM F. McDEVITT, OF SOUTH DORSET, VERMONT.

BAR COAL.

Application filed December 30, 1921. Serial No. 525,252.

To all whom it may concern:

Be it known that WILLIAM F. McDEVITT, a citizen of the United States, residing at South Dorset, in the county of Bennington 5 and State of Vermont, has invented certain new and useful Improvements in Bar Coal, of which the following is a specification.

This invention has relation to certain new and useful improvements in a machine for 10 manufacturing artificial fuel from waste products and has for its primary object the provision of a machine of the character stated which will be especially adapted for manufacturing a fuel from the waste products 15 of mines, commonly known as culm or waste coal or from peat and a pulp, properly mixed and treated chemically, then pressed into sheets and finally cut into strips and blocks and coated and dried as they 20 pass through these machines and previous to the cutting thereof, in strips or blocks.

The invention has for another object the provision of a machine of the character 25 stated which will be of special construction for the purpose of compressing the pulp mixture and producing therefrom the fuel strips or blocks at the minimum cost of manufacturing.

The invention has for a further object 30 the provision of a machine of the character stated in which the parts thereof will be simple in construction and arrangement and positioned and connected in such a manner as to thoroughly cooperate in the manner 35 designed for producing a practical artificial fuel which may be employed in various kinds of stoves and furnaces and considerably reducing the cost of operation of said stoves and furnaces and at the same time 40 utilizing material which has to the present time been considered more or less of a waste product.

The invention has for a still further object 45 the provision of a machine of the character above stated in which the various sets of rollers may be adjusted as the conditions may require and the other parts of the machine of such construction and arrangement that the machine may be provided at 50 the minimum cost while at the same time providing for the maximum efficiency of operation of the machine.

With the foregoing and other objects in view as will appear as the description pro-

ceeds, the invention consists in the novel 55 construction, combination and arrangement of cooperating elements as hereinafter more specifically set forth, claimed and shown in the accompanying drawings forming a part 60 of the present application and in which:—

Figure 1 is a side elevation of the complete machine constructed in accordance with the present invention.

Figure 2 is a top plan view of the machine as shown in Fig. 1.

Figure 3 is a longitudinal section through the machine with the exception of the mixing tanks and the operating means therefor.

Figure 4 is a transverse vertical section on the plane of line 4—4 of Fig. 3 of the 70 drawings, looking in the direction indicated by the arrows.

Figure 5 is a vertical section through the mixing tanks.

Figure 6 is a transverse section on the 75 plane of line 6—6 of Fig. 5, looking in the direction indicated by the arrows.

Figure 7 is a detail transverse section 80 through the strip cutting roller, as shown on line 7—7 of Fig. 2, looking in the direction indicated by the arrows, this view showing only the construction of the roller and illustrating the same on an enlarged scale.

Figure 8 is a detail transverse section 85 through the transverse or block cutting roller, showing this roller on a slightly enlarged scale with the cutting blades arranged therein, the view being taken approximately on the plane of line 8—8 of 90 Fig. 2 and showing only the roller construction.

Fig. 9 is a diagrammatic view of the conveying means.

Referring more in detail to the drawings 95 in which similar reference characters designate corresponding parts throughout the several views, 1 indicates the mixing tank which is mounted on a suitable supporting frame 2 and has a concaved or bowl-shaped bottom 3 so that the mixture from the tank 1 may readily pass out of the discharge spout 4 protected from the bottom 3 of the mixing tank 1 to the upper end of the inclined trough 5. This trough 5 is mounted 100 on suitable supporting members 6 preferably connected to form the frame 7 to support the trough 5. The trough 5 is also 105

2
preferably curved downwardly at its lower or forward end to form a discharge or spout 8 from which the finished artificial fuel strips or blocks may be discharged into a receiving member or the like, not shown.

The mixing tank 1 serves to mix a previously prepared pulp formed from a suitable material and preferably chemically treated before being placed in the tank 1, 10 with waste fuel material such as waste material from mines known commonly as culm or with peat. It is to be understood that the waste coal product or the waste wood product and the peat may be mixed in any suitable proportions with the prepared pulp and the entire mixture thoroughly agitated and mixed together within the tank 1. For properly mixing the contents of the mixing tank 1, I have provided a plurality of mixing bars or arms 9 of various lengths and depending from the rotary disk 10 carried on the lower end of a stub-shaft 11 projecting through the cover 12 for the top of the mixing tank 1. The cover 12 is shown in 25 Fig. 5 of the drawings as having a greater diameter than the disk 10 and resting upon the inwardly turned upper edge 13 of the tank 1, which edge 13 forms a supporting frame for the cover 12. A suitable collar 14 is carried on the stub-shaft 11, above the cover 12 to prevent longitudinal movement of the stub-shaft 11. This stub-shaft 11 has a bevel gear 15 mounted upon its upper end and adapted to be driven by a bevel gear 16 carried on one end of the stub-shaft 17. In 30 Fig. 2 of the drawings the stub-shaft 17 is shown as being positioned at approximately a right angle to the stub-shaft 11 and mounted in suitable bearings 18 supported 35 by the supporting frame 19 for the stub-shaft 11. This supporting frame 19 is shown as being carried by the upper portion of the mixing tank 1 as will be evident by referring to Fig. 1 of the drawings. It will 40 therefore be seen that the shafts 11 and 17 will be properly supported. It may also be seen by referring to Fig. 2 of the drawings that the shaft 17 has been illustrated as having a power receiving pulley 20 mounted 45 thereon to receive power from the main power belt 21 leading from a suitable source of power, not shown. This shaft 17 also has a pulley 22 mounted thereon with the power transmitting belt 23 engaged therearound, 50 said belt 23 being also extended around a pulley 24 carried on the lower roller shaft 25 of the first set of compressing rollers, as will be later more clearly understood.

A second or upper shaft 25 is positioned 55 above the lower shaft 25 and slightly forwardly thereof, the purpose of which will presently appear. A turned belt 26 connects corresponding pulleys 27 on the lower and upper shafts 25 so as to drive the upper and lower shafts 25 in opposite directions.

These shafts 25 have compressing rollers 28 mounted thereon transversely of the trough 5 with the lower roller 28 projecting a suitable distance through the transverse opening 29 in the bottom of the trough 5, while the upper roller 28 has its lower portion positioned a suitable distance below the upper edges of the side flanges 5' or longitudinal flanges or side members of the trough 5. An adjustable idler 30 is mounted for adjustment on the side flange 5' of the trough 5 so as to provide for tightening and loosening of the belt 26, as conditions may require. The mounting of the idler 30 is indicated at 70 75 80 85 90 95 100 105 110 115 120 125 130 31. The upper shaft 25 is mounted in suitable boxings or bearings 32 adjustable in the guide frame 33 carried on the opposite side flanges 5' of the trough 5. Suitable adjusting screws 34 are engaged through the upper end 35 of the frame 33 for raising and lowering the boxings or bearings 32 and thereby varying the distance between the upper and lower rollers 28. These upper and lower rollers 28 are positioned only a short distance forwardly of the discharge spout 4 and the relative adjustment of the rollers 28 will provide for proper compressing of the material as delivered to the rollers 28, as will be clearly understood by parties familiar with machines of this character. 125 One or more additional sets of plain compressing rollers 28 should be provided forwardly of the first set and mounted on shafts 25 as described for the first set. In the drawings forming a part of the present application, one additional set of plain compressing rollers 28 has been illustrated, although this may be varied as desired. These rollers are numbered the same as the first set of rollers 28 and the mountings and construction of the same corresponding with the first set, the main reference characters have been employed for the corresponding parts thereof and further details of description of this second set of rollers is believed to be unnecessary.

Additional lower shafts 25 are provided at suitable locations forwardly of the shafts 25 already described and each of these additional shafts 25 have a lower plain roller 28 mounted thereon and projecting slightly into the bottom of the trough 5, as will be readily understood by referring to the drawings. All of the shafts 25 beneath the trough 5 are mounted in suitable bearings 25', as shown in Fig. 1. A lower belt 36 extends around suitable pulleys 37 on each of the lower shafts 25 for rotating these shafts all together and in the same direction. Suitable tension rollers or idlers 38 are provided for the lower belt 36, between the lower shafts 25 and adapted to be retained in engagement with said lower belt 36 by the spring arms 39 upon which the tension rollers or idlers 38 are carried, said arms 39

being secured to the under face of the trough 5, as shown clearly in Fig. 3 of the drawings.

Above each of the additional lower shafts 25 is positioned an upper additional shaft 25 for cooperation therewith, as will be described. Each of these additional upper shafts 25 is mounted in suitable bearings or boxings 32, as described for the first mentioned upper shaft 25 and the boxings or bearings 32 for the additional upper shafts 25 are mounted for adjustment as described in connection with the first mentioned upper shaft 25. Therefore, the mounting of these additional upper shafts 25 will need no further detailed description as the same reference characters are employed as for the first upper shaft 25.

On the upper shaft 25 immediately forwardly of the last upper compressing roller 28 is positioned a slicing or stripping roller 40 which is shown as having a diameter greater than the plain compressing rollers and also carrying spaced circumferential knives or blades 41 for stripping the compressed material as it passes in the form of a sheet between the stripping roller 40 and the lower plain roller 28 opposite the same. This stripping roller 40 and the shaft 25 upon which it is mounted should be adjusted with respect to the corresponding roller 28 so that the blades or knives 41 will cut through the sheets of material passing between these rollers, thereby stripping the sheet or cutting the same into longitudinal strips.

On the last or lowermost upper shaft 25 is a transversely cutting roller 42. This roller 42 has longitudinal grooves 43 formed in its peripheral portion and extending inwardly a suitable distance to form pockets or slots for longitudinal blades or knives 44. These knives 44 may be securely held in the grooves or pockets 43 by tension screws 45 secured in the roller 42 and bearing upon the inner portions of the blades 44, as shown in detail clearly in Fig. 8 of the drawings. The blades 44 have bevelled free longitudinal edges and are positioned so that these edges are all extended in the same direction. The blades 44 are of such a size that proper adjustment of the shafts 25 on which the roller 42 is mounted will cause the blades 44 to cut through the strips of material as they pass between the roller 42 and the corresponding roller 28 cooperating therewith. This will result in cutting the strips of material into blocks of the desired size just previous to the discharging of the material from the discharge spout 8 or curved forward end of the trough 5.

Each of the upper shafts 25 throughout the lengths of the trough 5, is provided with a pulley 46 over which the upper belt 47 is engaged for rotating all of the upper shafts

25 in the same direction and opposite to the direction of rotation of the lower shafts 25, thereby causing the sets of upper and lower rollers to constantly operate to carry the compressed material forwardly. In order to retain the upper belt 47 under proper tension and thereby assure thorough cooperation of the upper and lower rollers, tension rollers or idlers 48 are constantly engaged with the upper end of the upper belt 47, as shown in Figs. 1, 2, 3 and 9 of the drawings. These tension rollers or idlers 48 are carried on the spring arms 49 attached in a suitable manner to the guide frame 33, as shown in Figs. 1, 2, and 3 of the drawings. Stationary lower idlers 50 are also preferably provided on the outer face of the adjacent side flange 5' of the trough 5 so as to keep the lower end of the upper belt 47 in engagement with the pulleys 46 of the upper shaft 25, as shown in Figs. 2 and 9 of the drawings. This is essential so that the material may be first thoroughly compressed in sheet form and then cut into strips and finally severed into blocks before being discharged from the machine. The effect of keeping the proper tension on said lower belt 36 and upper belt 47 at all times may be better appreciated by referring to Fig. 9 which discloses this feature clearly.

It is believed that the complete operation of the machine may be readily understood from the foregoing paragraph taken in connection with the accompanying drawings without further detailed description. It may be briefly stated, however, that by the employment of the machine as set forth in this application, the mixture after being thoroughly agitated and mixed in the mixing tank 1, is delivered by way of the discharge spout 4 into the upper end of the trough 5 and as it passes in sheet form between the compressing rollers 28 arranged in pairs at the upper portion of the trough 5, is fed with the greater portion of the liquid and chemicals pressed out of the material, to the first cutting or stripping roller above one of the lower plain rollers and then passed beneath the transversely cutting upper roller for the purpose of severing the strips into blocks and then discharging the same from the lower or discharge end 8 of the trough 5. If desired, the material may be coated with coal dust or the like previous to the stripping thereof and may also be dried as it passes from the stripping roller to the transversely cutting or block cutting roller, thereby making it possible to deliver a thoroughly dried and coated artificial fuel in block form from the discharge end 8 of the trough 5.

While the preferred embodiment of the invention has been shown and described, it is to be understood that minor changes in the details of construction and arrangement

of parts may be resorted to within the scope of what is claimed without departing from the spirit of the invention.

What is claimed is:—

- 5 1. An artificial fuel manufacturing machine comprising a trough, means mounted on said trough for compressing the material delivered thereto into sheet form, means mounted on the trough for cutting the sheets into strips, means mounted on the trough for cutting the strips into blocks previous to the discharge of the material from the trough, and operating mechanism for said mentioned means.
- 10 15 2. An artificial fuel manufacturing machine comprising a trough, a hopper associated with one end of said trough for feeding the contents thereof to said trough, rollers mounted on said trough in sets, certain 20 of said sets of rollers compressing the material into sheet form as it passes along said trough, certain of said rollers cutting said sheets into strips for the compressing thereof, certain of said rollers cutting said strips 25 of material into blocks before the discharge of the material from the trough, and means for operating said rollers.
- 30 3. An artificial fuel manufacturing machine comprising a hopper, an inclined trough, means extending from said hopper to deliver the contents thereof to the upper end of said trough, compressing rollers arranged in pairs along said trough, the rollers at the upper portion of said trough compressing the material passing therethrough into sheet form, certain of the compressing rollers cutting the compressed sheets into strips, certain of said rollers forwardly of the last mentioned rollers cutting the strips 40 into blocks, and means for operating said rollers simultaneously.
- 45 4. An artificial fuel manufacturing machine comprising a hopper, a trough associated with said hopper and receiving the contents therefrom, compressing rollers arranged along said trough, certain of said rollers compressing the material into sheet form, certain of said rollers cutting the sheets into longitudinal strips, one of the 50 last mentioned rollers having circumferential cutting members arranged thereon, additional rollers arranged to cut the strips transversely, one of the last mentioned rollers being provided with longitudinally mov-

able knives, the latter being detachably supported in said roller, one roller of each set along the trough being mounted for adjustment with respect to the corresponding roller, and means for operating said upper and lower rollers simultaneously in opposite directions.

5 5. An artificial fuel manufacturing machine comprising a hopper having a discharge spout at its lower portion, a trough arranged on an incline and adapted to receive the material discharged from said hopper, rollers arranged in sets above and below the trough at spaced intervals throughout the length thereof, certain of said rollers compressing the material received in the trough from the hopper into sheet formation, a further set of rollers including a roller having means for cutting the material into strips, another set of rollers including a roller having means for cutting the strips into blocks before the discharge of said material from said trough, separate operating means for the upper and lower rollers of the sets, and tensioning means associated with said operating means.

6 6. An artificial fuel manufacturing machine comprising a hopper, a trough to receive the material from said hopper, means mounted on said trough for compressing the material delivered thereto from said hopper and pressing the same into sheets, means for cutting the compressed sheets into blocks before the discharge of the material from said trough.

7 7. An artificial fuel manufacturing machine comprising a hopper, a trough for receiving the contents of said hopper, supporting means for said trough, rollers arranged in sets above and below said trough the lower rollers extending into the bottom of said trough the upper rollers being adjustable with respect to the lower rollers, means for operating the upper and lower rollers in opposite directions to carry the material longitudinally through said trough, said rollers cooperating to compress the material, certain of said rollers cutting the material longitudinally and transversely forming blocks as it passes in sheet formation through the trough.

In testimony whereof I affix my signature.

WILLIAM F. McDEVITT.
